UNITED STATES PATENT OFFICE.

HUGH W. BATCHELLER, OF WORCESTER, MASSACHUSETTS, ASSIGNOR TO WORCESTER ELECTRIC SUPPLY COMPANY, A CORPORATION OF MASSACHUSETTS.

DESIGN FOR A DASH LAMP.

Application filed November 1, 1922. Serial No. 4,182. Term of patent 3½ years.

To all whom it may concern:

Be it known that I, HUGH W. BATCHELLER, a citizen of the Dominion of Canada, residing at Worcester, in the county of Worcester and State of Massachusetts, have invented a new, original, and ornamental Design for Dash Lamps, of which the following is a specification, reference being had to the accompanying drawing, forming a part thereof.

I claim:

The ornamental design for a dash lamp, as shown.

In testimony whereof I have affixed my signature.

HUGH W. BATCHELLER.
